UNITED STATES PATENT OFFICE

154,142

DESIGN FOR A WRIST BAND

Alfred Pinson, Stamford, Conn., assignor to Apex
Accessories Co., Inc., New York, N. Y.

Application March 16, 1949, Serial No. 1,426

Term of patent 14 years

(Cl. D45—4)

To all whom it may concern:

Be it known that I, Alfred Pinson, a citizen of the United States, residing at Stamford, in Fairfield County, State of Connecticut, have invented a new, original, and ornamental Design for a Wrist Band, of which the following is a specification, reference being had to the accompanying drawing, forming part thereof.

Figure 1 is a perspective view of the wrist band showing my new design.

Figure 2 is a fragmentary side elevational view on an enlarged scale of one end of the band.

Figure 3 is a top plan view of the fragment of the band shown in Figure 2; and

Figure 4 is an end elevation of the band.

I claim:

The ornamental design for a wrist band, as shown.

ALFRED PINSON.
